UNITED STATES PATENT OFFICE.

FREDERICK A. ONSTINE, OF CLEVELAND, OHIO.

SAW.

Specification of Letters Patent.

Patented Feb. 23, 1915.

1,129,595.

Application filed January 6, 1913. Serial No. 740,273.

To all whom it may concern:

Be it known that I, FREDERICK A. ONSTINE, a citizen of the United States, residing at Cleveland, in the county of Cuyahoga and State of Ohio, have invented new and useful Improvements in Saws, of which the following is a specification.

My invention relates to saws and has particular reference to saws having means whereby the blades may be easily and quickly removed and replaced, and whereby they may be held securely in place.

My invention also relates to means for adjusting the tension on the blades and for compensating for slight variations in the length of the same.

Further objects will appear hereinafter.

Referring to the accompanying drawings, Figure 1 is a side elevation of a saw to which my invention has been applied; Fig. 2, a vertical section of a portion of the saw, showing the internal structure of the portions in which my invention particularly resides; Fig. 3, a perspective view of the lever for locking the blade to the saw and giving the latter the desired tension; Fig. 4, an end view of the said lever looking toward the left at Fig. 1; Fig. 5, a bottom view of the said lever; and Fig. 6, a perspective view of the adjustable wedge carried by the lever.

On the drawings, the frame of the saw is composed of metal and has the back 1, the front arm 2, and the rear arm 3. The arms 2 and 3 are provided with slots to receive the saw-blade 4, the slot in the rear arm being marked 5. The front edge of the arm 2 has the slot 6 to receive the transverse pin 7 secured to the blade 4. The rear edge of the arm 3 has the rounded notch 8 near the end thereof, having the projection or fulcrum 8' for the lever 9.

16 is the handle secured to the frame at or near the junction of the back 1 and the rear arm 3.

45 The body of the lever 9 is a block or piece of metal having a kerf or slot 11 which is open at its under side and extends upwardly a sufficient distance to accommodate the rear end of the blade 4. The front edge of the lever is channeled or grooved, as at 12, from the top downwardly, there being near the lower end of the groove 12 the forwardly curved projections 13, one on each side of the slot 11, in which they obviously lie when 55 the lever is rocked from the position shown in Fig. 2, to that shown in Fig. 1. Pref-

erably the projections 13 are slightly within the front edges of the flanges or side walls 14 which define the sides of the slot and embrace the sides of the arm 3 when 60 the lever is in the position shown in Fig. 1, and in the dotted position shown in Fig. 3. Preferably the projections do not quite reach the lower end of the groove 12, thereby leaving a shoulder or depression 15 at 65 each side of the slot 11 to receive the fulcrum 8' at each side of the said slot. The lever 9 has at its rear upper corner the upwardly and forwardly curved operating arm 16. The rear edge of the lever has the 70 open-ended slot 17 to receive the transverse pin 18 secured in the rear end of the saw blade.

The rear portion of the slot 11 is widened at each side, as shown at 19 to provide a 75 space for the vertical wedge 20, having a vertical back in engagement with the front wall of the slot 19. The rear edge of the wedge 20 is inclined upwardly and toward the front wall of the slot 19. The wedge has 80 the slot 21 in line with the slot 11 to receive the blade 4. The upper end of the wedge has the screw threaded stem 22 which extends up through the top wall of the slot 19 and is provided with the nut 23, bearing 85 on the top of the body of the lever 9.

The front end of the blade 4 is inserted in the arm 2 with the pin 7 in the slot 6. The lever 9 is placed as in Fig. 2 with the fulcrum 8' preferably in the notch 15, and 90 the pin 18 in the slot 17 and against the rear edge of the wedge 20. The lever is then moved to the dotted position (Fig. 2) or the position shown on Fig. 1, causing the arms 2 and 3 to be slightly sprung toward 95 each other and the pin 18 to pass the dead center with respect to the fulcrum 8'. The strain put on the arms 2 and 3 is exerted, when the lever is in the position shown on Fig. 1, to hold the lever firmly in contact 100 with the rear edge of the arm 3 and to keep the blade tightly stretched. The blade may be easily and quickly removed by inserting the finger in the lever arm 16 and rotating the lever to the full line position (Fig. 2) 105 when the lever can be removed from the arm 3 and the blade can be easily taken out of the lever, or allowed to drop out of the same. The tension of the blade can be adjusted by operating the nut 23 to raise or 110 lower the wedge 20, whose rear edge controls the rearward position of the pin 18. When

the wedge is raised, the pin 18 is seated farther to the rear in the slot 17, so that the tension on the blade is increased, or a slightly longer blade may be used.

5. The lever 9 is preferably thicker than the front arm 2, owing to the insertion of the wedge in the lever. This permits the use of a longer cross-pin at the rear end of the blade than at the forward end without the 10 ends of the pin extending beyond the faces of the lever. The provision of a longer pin on one end of the saw blade enables it easy to get the blade into the frame with the 15 teeth of the blade pointing in the proper direction.

While I have shown and described my invention in detail, I do not desire to be restricted to the combinations and details 20 shown and described, as the same can be varied considerably within the scope of the appended claims.

I claim—

1. In a saw, a U-frame, a saw blade connected at one end to the front arm thereof, 25 a lever pivotally connected to the other end of the blade and to the rear arm of the frame, and means carried by the lever and movable relatively to the lever and transversely of the blade and engaging with the 30 pivotal connection between the lever and the blade for adjusting the tension of the blade.

2. In a saw, a U-frame, a saw blade connected at one end to the front arm thereof, 35 a lever for connecting the other end of the blade to the rear arm of the frame, and a wedge movable transversely of the blade carried by the lever for adjusting the connection thereof with the saw blade.

40 3. In a saw, a U-frame, a saw blade connected at one end to the front arm thereof and provided at the other end with a cross pin, a lever supported by the rear arm of the frame, and a wedge carried by the lever and 45 adjustable transversely of the blade for en-

gaging the cross pin and adjusting the tension of the saw blade.

4. In a saw, a U-frame, a saw blade connected at one end to the front arm thereof and extending at the other end to the rear 0 of the rear arm of the frame, a tension device for the blade operating between the said rear arm and the rear end of the blade, and a wedge movable transversely of the blade carried by the tension device for adjusting 55 the tension of the blade.

5. In a saw, a U-frame, a saw blade connected to one end thereof, a lever co-operating with the other end of the frame and the saw blade to connect the latter to the 60 frame, and a wedge carried by the lever and adjustable therein transversely of the blade to vary the tension of the saw blade.

6. In a saw, a U-frame, a saw blade connected at one end to the front arm thereof 65 and having a cross-pin at its rear end, a lever normally engaging the rear edge of the rear arm of the frame, the lever having a slot in its rear edge, a wedge lying across the slot and having its rear edge engaging the 70 cross-pin, and means for adjusting the wedge longitudinally to vary the position of the cross-pin in the slot.

7. In a saw, a saw blade, and a lever to tension the same, the lever having a rear 75 groove, a slot for the saw blade extending from the base of the groove to the rear of the lever, a slotted wedge movable cross-wise of the saw blade and seated in the widened rear part of the slot in the lever, a slot in the 80 rear edge of the lever, means for adjusting the wedge longitudinally, and a cross-pin on the saw blade in engagement with the rear edge of the wedge.

Signed at Cleveland, Ohio this 21st day of 85 December, A. D. 1912.

FREDERICK A. ONSTINE.
